UNITED STATES PATENT OFFICE.

HENRY F. COLVIN, OF PHILADELPHIA, PENNSYLVANIA.

MECHANISM ILLUSTRATING STEAM-ENGINE VALVE-MOTIONS OF DIFFERENT CONSTRUCTIONS.

SPECIFICATION forming part of Letters Patent No. 718,193, dated January 13, 1903.

Application filed November 1, 1902, Serial No. 129,660. (No model.)

To all whom it may concern:

Be it known that I, HENRY F. COLVIN, a citizen of the United States, residing at Philadelphia, in the county of Philadelphia and State 5 of Pennsylvania, have invented certain new and useful Improvements in Mechanism Illustrating Steam-Engine Valve-Motions of Different Constructions, of which the following is a specification.

10 This invention relates to mechanism for the diffusion of knowledge in regard to steam-engine valves and their operative mechanism.

The construction is of a size to be readily portable, while exhibiting full-size valves and 15 valve-faces, with full-size ports and valve travel up to the limit in use. Its various parts being compact, its cost will be so slight as to permit its introduction generally into club and lodge rooms of mechanical societies, 20 schools, and scientific associations, as well as to private students interested in steam-engine construction and operation. It shows in full size the control of the induction and eduction ports by the valve, the effect of lap and lead 25 as produced by different valve motions and travel and as influenced by eccentrics or other prime movers when in advance of the crank or following it, the position of the piston and cross-head at the time of cut off and 30 release, with increase or decrease of lead or uniform lead through all points of cut-off, the amount of compression due to the time of release or opening of the induction-ports.

The mechanism is designed for and adapted 35 to illustrate the working of the valve of any form or proportion of engine and with either slide or piston valves.

The accompanying drawings, in which similar parts are referred to by similar reference 40 characters, illustrate the invention, and in which—

Figure 1 is a front elevation view showing the valve and valve-seats with their ports and openings. Fig. 2 is a vertical central section 45 on line *x x*, Fig. 1. Fig. 3 is a rear elevation view showing the crank and motion-plate with its slots for different forms of valve-moving mechanisms. Fig. 4 is a longitudinal central section on line *v v*, Fig. 3.

50 A plate 1 is the foundation for the working parts, and it may be either of rectangular form, as shown, or, if desired, of oval or circular form, and it is supported by standards 2 3, as shown, or other suitable form, removably

secured by screws and thumb-nuts 4 5 for 55 convenience in stowing away for portability. At the center of plate 1 a circular aperture 6 is formed, and therein an annular ring 7 is fitted to rotate, the ring being of slightly-greater width than the thickness of plate 1, 60 as seen in Figs. 2, 4, and secured to ring 7 by rivets 8 or other suitable means is an annular disk 9 in front of plate 1 and a disk-crank 10 at the back of the plate. Disk 9 and crank 10 are of greater diameter than ring 7 and overlap 65 plate 1. This secures them sidewise outside of the plate, where they are free to turn without friction against the plate, the crank having a handle 11 for such purpose. In front of disk 9 is a plate 12, slightly shorter than plate 1 and 70 secured for reciprocating movement by guides 13 14 with cover-plates 15 16, which are also clips for securing the removable valve-seat cards, which are hereinafter described. Plate 12 has attached thereto one end of the long 75 member 17 of a parallel-motion connecting-rod in a slot 18, and at the other end it is attached to a motion-plate 19 at the back of crank 10, the motion-plate being secured by thumb-nuts and screws 20, passing through 80 slots 21, to permit the adjustment of the plate. A short member 22 of the connecting-rod is attached at one end to member 17, and at its opposite end it is secured to the reciprocating motion-plate 12 at its center. The mem- 85 bers 17 22 form a parallel motion. In plate 19 is a central vertical straight slot 23, representing and used for valve-motions having a uniform lead, and at each side are reversely-curved slots 24, representing and used for 90 valve-motions having an increasing lead, and 25, representing and used for valve-motions having a decreasing lead. Scales 26 are shown on plate 19 for the convenience of accurate adjustments of the plate either way 95 from zero-lines 28, equivalent to the angularity at which the eccentrics or other prime movers are set to work off the lap and lead at the commencement of the stroke, lines 29, being the centers of slot 24, coinciding with 100 lines 28, and lines 30, being the centers of slot 25, coinciding with lines 28. Upon the reciprocating motion-plate 12 is a card representing a common D-valve 31, removably secured by clip 32, which in turn is held by 105 screw and thumb-nut 33. Disk 9 is graduated in inches of its rotary movement corresponding to the inches of reciprocating move-

ment of a piston and cross-head of the same stroke, but commencing at right angles to the crank's dead-centers, and above and below the disk, upon plate 1, are lines 34, representing 5 the dead-centers of the crank and the commencement and ending of each stroke. This arrangement facilitates the reading of the piston travel, as the disk divisions and figures are always in sight when approaching 10 lines 34. Plate 13 supports a removable card 35, representing a valve-seat, and is secured by clips 15. For slide-valves in which the steam passes through the valve and also for piston-valves an additional card may be 15 placed on plate 14 and secured by clips 16. Plate 19 has horizontal graduating lines 36, representing an eccentric's throw or its concentric path or representing the movement of other prime movers where eccentrics are not 20 used. As illustrated, the rod 17 being secured in slot 23 of motion-plate 19 the rotation of crank 10 will move valve 31 forward and back each way an amount equal to twice the distance at which rod 17 is secured in 25 slot 23 beyond its center. When plate 19 is set over to represent the corresponding angular position of the eccentrics or the prime mover, due to lap and lead, the mechanism will then correctly control the valve to indicate 30 its action in connection with the steam and exhaust ports and the piston and crank movements, and the same will be true when the rod 17 is attached in slot 24 or slot 25.

I claim--

- 35 1. In a mechanism of the character described, a foundation-plate, a disk graduated to indicate circular movements equivalent to the same amount of reciprocating movements, and placed at one side of the plate, and a 40 disk-crank at the opposite side of the plate, the disk and crank being secured together and supported by the plate for free rotary movement.
- 45 2. In a mechanism of the character described, a foundation-plate, an aperture therein, an annular ring in the aperture, an annular disk secured at one edge of the ring, a disk-crank secured at the opposite edge, the disk and crank extending outward beyond the 50 ring and clear of the plate; lines upon the plate at right angles to the crank's dead-centers, graduations upon the annular disk spaced to indicate a crank's rotary movement equivalent in amounts or distances to the reciprocating movements of a piston having the 55 same stroke, the commencement and ending of the crank and piston stroke as indicated on the disk, coinciding with the lines on the plate aforesaid.
- 60 3. In a mechanism of the character described, a graduated disk and a crank supported for rotary movement, a plate opposite thereto and guided for reciprocating movement, and means to connect the crank to the 65 plate for its movement.
- 65 4. In a mechanism of the character described, a disk and a crank, means for their

connection and support for rotary movement, a plate guided for reciprocating movement, means for its driving by the crank, and means 70 to removably secure representations of valves thereon.

5. In a mechanism of the character described, a disk and a crank, means for their connection and support for rotary movement, 75 an oppositely-supported plate guided for reciprocating movement, means for its driving by the crank, means to removably secure representations of valves thereon, and means to removably secure above and below the valve 80 representations of valve-seats.

6. In a mechanism for the purpose described, a rotatable disk and crank secured for unison in movement, a plate guided for reciprocating movement, a motion-plate adjustably secured to the crank, means to connect the motion-plate to the reciprocating moving plate in manner to regulate the amount of reciprocating movement.

7. In a mechanism such as described, a 90 crank and a disk connected and supported for rotary movement, a plate guided for reciprocating movement, a motion-plate secured to the crank for movement toward or from the crank's arm, graduations for the 95 amount of movement, a straight slot in the plate at a right angle to the crank, and a parallel-motion connecting-rod comprising two members, the longer one yieldingly connected to the reciprocating motion-plate at one 100 end and to the slot aforesaid in the motion-plate at its other end, and its shorter member connected at one end to the center of the reciprocating motion-plate, and to the longer member at the other end. 105

8. In a machine such as described, a crank and a disk united and supported for rotary movement, a reciprocating movement-plate, a motion-plate adjustably secured to the crank, a central straight slot therein, and 110 at each side thereof reversely-curved slots, a parallel-motion connecting-rod comprising two members, one of said members being yieldingly connected to the reciprocating movement-plate at one end, and adapted to 115 engage one of the aforesaid slots at its opposite end, the other member being connected to the reciprocating movement-plate at its center, at one end, and to the first-mentioned member at its opposite end, and a graduated 120 scale to indicate the position of the connecting-rod in the slots.

9. In a mechanism as set forth, a rotatable crank and disk, a reciprocating plate, means for their connection and operation as set 125 forth, representations of a valve and its seats, and supports for the apparatus detachably secured, to facilitate portability.

In testimony whereof I affix my signature in presence of two witnesses.

HENRY F. COLVIN.
